US00D591691S

(12) **United States Design Patent**
Baker et al.

(10) **Patent No.:** US D591,691 S
(45) **Date of Patent:** ** May 5, 2009

(54) **OVERVOLTAGE PROTECTION PLUG**

(75) Inventors: **Scott K. Baker**, Richfield, MN (US);
Cyle Petersen, Belle Plaine, MN (US)

(73) Assignee: **ADC Telecommunications, Inc.**, Eden Prairie, MN (US)

(**) Term: **14 Years**

(21) Appl. No.: **29/273,234**

(22) Filed: **Feb. 28, 2007**

(51) **LOC (9) Cl.** 13-03

(52) **U.S. Cl.** D13/160; D13/124

(58) **Field of Classification Search** D13/133, D13/154, 161, 160, 124; 439/717, 721, 725
See application file for complete search history.

(57) **CLAIM**

The ornamental design for an overvoltage protection plug, as shown and described.

DESCRIPTION

FIG. 1 is a front perspective view of an overvoltage protection plug showing our new design;

FIG. 2 is a rear perspective view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof; and,

FIG. 8 is a bottom plan view thereof.

The broken line portion of the figure drawings is included to show unclaimed internal elements within the shell of the design only and forms no part of the claimed design.

1 Claim, 6 Drawing Sheets
